UNITED STATES PATENT OFFICE.

ADOLPH PETZOLD, OF PHILADELPHIA, PENNSYLVANIA, ASSIGNOR TO JOHN H. BROMLEY AND EDWARD BROMLEY, OF SAME PLACE.

DESIGN FOR A RUG.

SPECIFICATION forming part of Design No. 27,683, dated September 21, 1897.

Application filed August 13, 1897. Serial No. 648,178. Term of patent 3½ years.

To all whom it may concern:

Be it known that I, ADOLPH PETZOLD, a citizen of the United States, residing at the city of Philadelphia, State of Pennsylvania, 5 have invented and produced a certain new and original Design for a Rug, of which the following is a full, clear, and exact description, reference being had to the accompanying drawing, forming a part of this specification.

10 My invention relates to the surface ornamentation of a woven rug; and it consists of the design therefor shown in the aforesaid drawing, the distinguishing features of which comprise the outer rectangular border *a*, composed of a series of rosettes between parallel straight lines, and an inner double-line rec-

15

tangular border *b*. Between the same is a series of shell figures *c*, connected by a straight line run through them. The field-center is composed of a center diamond-shaped figure 20 *d*, and at each end are irregular figures *e* and floral figures *f*.

I claim—

The design for a rug substantially as set forth.

In testimony whereof I have hereunto affixed my signature this 8th day of July, A. D. 1897.

ADOLPH PETZOLD.
